Patented May 9, 1922.

UNITED STATES PATENT OFFICE.

JOHN J. HOPPS, OF LAWTON, OKLAHOMA, AND CARL W. HOPPS, OF WESTFIELD, NEW JERSEY.

COMBINED HORN AND RETURN BALL.

1,415,350.

Specification of Letters Patent. Patented May 9, 1922.

Application filed June 3, 1920. Serial No. 386,342.

To all whom it may concern:

Be it known that we, JOHN J. HOPPS and CARL W. HOPPS, citizens of the United States, residing at Lawton and Westfield, 5 in the counties of Comanche and Union, and States of Oklahoma and New Jersey, have invented certain new and useful Improvements in Combined Horns and Return Balls, of which the following is a specification.

This invention relates to toys and more particularly to an improvement in toys of the return ball type, the general object of the invention being to provide a combined 15 horn and return ball so constructed that the ball, when thrown, will be returned to position within the horn.

Another object of the invention is to so construct the device that the return ball 20 will be retained within the bell of the horn and thus normally concealed from view although it may be readily thrown in any direction by a swing of the horn in the same 25 direction.

Another object of the invention is to provide for normal retention of the ball within the horn in such a manner as to not in any way interfere with blowing of the horn.

A further object of the invention is to 30 so construct the horn as to provide means for preventing the ball becoming tightly wedged within the horn or so filling or closing the horn as to prevent blowing of the latter.

Another object of the invention is to so 35 connect the elastic element of the device with the ball and horn that the said ball will be returned into the horn without the necessity of exercising skill, although the use 40 of the device in throwing the ball will influence one to exercise skill in catching the ball within the horn without the ball striking the periphery of the mouth or bell of the horn.

In the accompanying drawings:

Figure 1 is a view partly in side elevation and partly in longitudinal section illustrating the device embodying the present invention;

Fig. 2 is a vertical transverse sectional view on the line 2—2 of Fig. 1.

In the drawings the numeral 1 indicates in general a horn which may be made of sheet metal or any other suitable material 55 and which is for the greater part of the

usual straight tapered form. The horn is provided at its minor end with the usual reed 2 and with a mouthpiece 3 which is fitted in any suitable manner to this end of the horn and which may be of wood or any 60 other material found suitable for the purpose. Near its outer or major end, the horn is formed with a bell 4 which is outwardly circumferentially bulged in a more or less pronounced manner as indicated by the numeral 65 5 for a purpose to be presently explained. Beyond the bulge 5, the bell 4 is flared as at 6 to form the mouth 7 of the horn, the inner surface of the mouth 7 and the inner surface of the bulged portion 5 70 of the bell 4 merging on rounded lines as indicated by the numeral 8.

The return ball heretofore referred to is indicated by the numeral 9 and the same may be of rubber or any other material or 75 a composition of materials, and connected to this ball is one end of an elastic element 10 which extends longitudinally within the horn and at its opposite end is threaded through an opening 11 formed in the said 80 horn near the minor end thereof and either knotted or secured to a button 12 exteriorly of the horn so as to be secured in place at this end. The normal length of the element 10 is such that the ball 9 will rest within the 85 concavity of the bulge 5 of the bell 4 as clearly shown in Fig. 1 of the drawings and as this bulge extends entirely circumferentially of the bell, the ball will occupy this position regardless of the rotation of the 90 horn to different positions about its longitudinal axis. Also when the ball occupies this normal position, it will be substantially concealed from view and therefore more or less surprise will be occasioned when the ball 95 is thrown from the horn.

It will be understood at this point that with the ball in its normal position as shown in Fig. 1, the horn may be blown without interference on the part of the ball, the ball 100 being of a diameter somewhat less than that of the bell at its bulged portion 5. When the ball is to be brought into play, the horn may be grasped and given a more or less sharp swinging or throwing motion with the hand 105 in the direction which the ball is to be thrown whereupon the ball will be forcibly ejected from the horn against the tension of the element 10 until the elasticity of this element overcomes the energy of the ball 110

whereupon the said elastic element will immediately act to return the ball in the general direction of the mouth of the horn, and inasmuch as the said elastic element extends 5 into the interior of the horn, the ball will finally be drawn into the bell of the horn through the mouth 7. The rounded surface 8 of the mouth will permit of the elastic element 10 riding in contact therewith without likelihood of being worn or cut, and inasmuch as the mouth is flared, the ball will be enabled to more readily pass into the bell than would otherwise be the case.

The ball will, of course, be somewhat 15 forcibly returned to position within the bell of the horn and may therefore be drawn into the horn to a position inwardly of the bell 4 and if the wall of the horn were of true conical form, it is probable that the ball 20 would become wedged more or less tightly within the horn thus not only requiring its dislodgment but likewise preventing blowing of the horn. In order to overcome this difficulty we stamp or otherwise form in the 25 wall of the horn any suitable number of flutes 13 which extend longitudinally of the said wall and which are preferably gradually increased in width and depth from their inner to their outer ends and have their said 30 outer ends formed more or less blunt and deep as clearly illustrated in Fig. 1 of the drawings and as indicated by the numeral 14. Thus the wider ends of the flutes are 35 presented in the direction of the mouth end of the horn and effectually form abutments against which the return ball may strike when withdrawn into the horn by the elastic element 10 and thus be arrested in its movement and prevented from becoming wedged 40 within the horn, it being understood that the inner sides of the flutes at their outer ends touch a circle of a diameter somewhat less than that of the ball.

It will be understood that when the device 45 is employed to bring into play the return ball, the horn will constitute a receiver for the said ball and that while we consider the combination of the horn and ball to be an exceptionally desirable one inasmuch as the 50 horn serves not only its primary purpose but also the additional purpose of a receiver for

the ball, it will be understood that aside from this combination the invention contemplates the general combination of a receiver, a return ball, and an elastic element connected with the ball and extended into the receiver and connected therewith.

Having thus described the invention, what is claimed as new is:

1. In a device of the class described, a receiver of hollow tapered form provided interiorly near its major end with an abutment, a ball, and an elastic element connected with the ball and extending into the receiver and connected therewith inwardly of 60 the abutment, the receiver between its said end and the said abutment being formed with an outwardly circumferentially bulged bell.

2. In a device of the class described, in 70 combination, a horn provided in its wall with longitudinal flutes having ends presented toward the mouth end of the horn, a ball, and an elastic element connected with the ball and extending into the horn and connected to the wall of the horn at a point inwardly of the said flutes, the ball being of a diameter greater than that of a circle touching the inner sides of the flutes and less than that of the horn adjacent the ends of 75 the flutes.

3. In a device of the class described, in combination, a horn provided in its wall with an outwardly circumferentially bulged bell located near its major end, a ball, and an 80 elastic element connected with the ball and extending into the horn and connected to the wall thereof near the minor end of the horn, the said elastic element being of a normal length such as to enable the ball to normally occupy a position within the concavity of the bulged bell, the wall of the horn being provided with longitudinal inwardly projecting flutes having ends presented toward the mouth end of the horn and constituting 85 a stop limiting the movement of the ball into the horn.

In testimony whereof we affix our signatures.

JOHN J. HOPPS. [L.S.]
CARL W. HOPPS. [L.S.]
